UNITED STATES PATENT OFFICE.

BERNARD J. CALLAN, OF NEW CASTLE, PENNSYLVANIA, ASSIGNOR TO JOHNSON BRONZE COMPANY, OF NEW CASTLE, PENNSYLVANIA, A CORPORATION OF PENNSYLVANIA.

CONTROL ATTACHMENT FOR ENGINE LATHES.

Application filed January 4, 1927. Serial No. 158,994.

This invention relates to engine, or machine lathes, and more particularly to a carriage control attachment therefor.

In an engine lathe, there is provided a carriage reciprocable along the bed of the lathe. This carriage may be operated in either direction, either by hand or through gearing driven by the lathe. The control lever for the automatic drive is, in the ordinary lathe, always positioned on the apron of the carriage at the end of the carriage most remote from the head stock of the lathe. This arrangement is highly satisfactory for most classes of work, but is not convenient for the turning of small objects such as sleeves and bushings where the machine is operated at a relatively high speed and where the piece has to be frequently changed. In the standard lathe, the operator has to use that hand for controlling the automatic feed which he also uses for placing pieces in the automatic chuck of the lathe or for removing finished pieces from the chuck. Consequently the location of the control lever is not well suited for this class of work.

According to the present invention, it is proposed to provide an attachment which will permit of the operation of the control lever from the opposite end of the carriage so that the operator does not need to use the same hand for starting and stopping the carriage which he uses for placing bushings on the chuck and removing them from the chuck.

According to the present invention, it is also proposed to provide an attachment wherein the automatic clutch and the carriage control attachment can be operated in unison so that the operator can accomplish with one hand, by the movement of a single lever, an operation that heretofore has required the use of both hands.

A further object of the invention is to provide a control attachment which is manual, or semi-automatic, the arrangement being such that the carriage will automatically reverse itself after a predetermined distance

of travel, but wherein the movement of the carriage in either direction can be stopped at any time.

The invention may be readily understood by reference to the accompanying drawings in which—

Figure 1 represents a side elevation of a portion of a standard engine lathe having a well known type of automatic clutch and having my invention applied thereto.

Figure 2 is a detail view on an enlarged scale showing the adjustable stops for determining the movement of the travel of the carriage.

Figure 3 is a detail view showing the operating connection between the clutch operating handle and the carriage control mechanism.

In the drawings, 2 designates the bed of a lathe having the usual head stock 3 and usual driving pulley 4. The spindle 5 of the lathe is provided with a clutch at 6, and an automatic chuck mechanism 7. The clutch and automatic chuck are of a type now generally well known, and form no part of the present invention. The arrangement is such that the automatic chuck and the clutch may be simultaneously operated by the movement of an operating handle 8.

Movable along the bed 2 of the lathe is a carriage 9 having a depending apron 10 thereon. On the carriage is the usual adjustable tool post 11. The carriage is provided with the usual automatic driving means operated from a lead screw 12, and including a reversing gear designated generally as 13 driving a pinion 14 for engagement with the rack 15 on the bed of the lathe. This general arrangement is quite common in engine lathes.

Carried on the apron of the lathe carriage is a control lever 16 for operating the reversing gear 13. This operating lever is in the position where it is generally located on all machine lathes, this position being at that end of the carriage most remote from the head stock 3.

According to the present invention,

bracket 17 is secured to the carriage on that end nearest the head stock and pivoted to this bracket at 18 is a lever 19. The lower end of the lever 19 is pivotally connected to a link 20, and the other end of the link 20 is pivotally connected to the control lever 16. The distance through which the lever 19 may be moved is limited by stops 21 on opposite sides of the bracket 17. On the lever 19 is a spring projected detent pin 22 for engagement with recesses 23 in the bracket. In the intermediate position, the lever 19 holds the lever 16 in a neutral position. A movement of the lever 19 in either direction from the neutral position shifts the lever 16 to operate the reversing drive mechanism 13 to cause the carriage to travel in the desired direction.

With such an arrangement the travel of the carriage can be controlled by the operator with his left hand, leaving his right hand entirely free for the application of bushings to the chuck and the removal of machined bushings therefrom.

According to the present invention, it is further proposed to provide means whereby the movement of the carriage may, in addition be automatically controlled to a certain extent. To this end a rod 24 is mounted in a bracket 25 on the frame of the lathe. On this rod are spaced apart stop members 26. These members, which are in the nature of collars, are adjustable on the rod and can be fixed by means of set screws 27. Each collar is preferably provided with a spring projected cushioning pin 28. The pins 28 are turned in opposite directions and are located in the path of movement of the lever 19. When the carriage moves in one direction to a predetermined extent the lever 19 comes into contact with the cushioning pin 28 of one of the stop collars. As the carriage continues to move while the stop collar holds the lever against movement the lever will be shifted. A predetermined movement of the carriage in the opposite direction will bring the stop lever 19 into cooperative engagement with the cushioning pin 28 of the other collar. In Figure 2 the arrangement is clearly illustrated; the view showing the position of the lever 19 just before it comes into engagement with one of the stop collars.

Inasmuch as it is necessary to stop the lathe to remove finished bushings or other articles being turned and substitute bushing to be finished, the present invention proposes to provide a connecting link between the lever 19 and the chuck controlling lever 8. Connected to the upper end of the lever 19 is a clevis 29 having one end of a link 30 pivotally connected thereto at 31; the other end of the link 30 is threaded. The threaded portion of the link passes through a spherical

bearing 31 in a boss 32 on the operating lever 8. On the link 30 at each side of the boss 32 are nuts 33. The arrangement is such that the link 30 may slide through the spherical bearing 31 a predetermined distance. However the nuts 33 limit this free movement and the arrangement is such that when the lever 8 is rocked from one position to another a corresponding movement can be imparted to the lever 19. The arrangement permits of the necessary amplitude of movement for the lever 8 without requiring that the lever 19 be rocked to the same extent. The arrangement also permits the carriage to travel back and forth without necessarily operating the lever 8.

The advantages of the invention arise from the provision of a control lever so disposed that the operator can use his right hand for removing and placing the bushings in the chuck while controlling the movement of the lathe carriage with his left hand. A further advantage of the invention resides in the provision of stop means for automatically determining the movement of the carriage and for controlling the movement of the carriage. Still a further advantage of the invention resides in the lost motion connected between control lever 19 and the control lever 8. This last mentioned arrangement permits of the stopping and starting of the lathe and the stopping and starting of the carriage simultaneously and with a single movement of the lever 8.

While I have illustrated a specific embodiment of my invention, it will be understood that the invention may be otherwise embodied and that various modifications and changes may be made in the construction illustrated within the spirit of my invention and under the scope of the appended claims.

I claim:

1. The combination with an engine lathe having a carriage movable therealong, driving means for the carriage; a lever at one side of the carriage below the top of the carriage for controlling the operation of said driving means, a vertically disposed operating lever pivotally mounted at the other end of the carriage and projecting above the top of the carriage, and a link connecting said operating lever with said first lever.

2. The combination with an engine lathe having a head stock, a bed, a carriage reciprocable along the bed, and means for driving the carriage, or means for controlling the operation of the driving means, and a vertically disposed operating lever on the carriage at the end of the carriage nearest the head stock and having an operating extension projecting above the bed of the lathe for operating said carriage controlling means.

3. A control attachment for engine lathe

carriages, having a control lever at one end of the carriage comprising a vertically extending operating lever pivotally mounted between its ends on the opposite end of the carriage with one end projecting above the top of the carriage, and a link connecting the operating lever with the control lever.

4. The combination with a lathe having a frame and a carriage reciprocable along the frame, automatic means for driving the carriage, a control for said driving means, a vertically disposed operating lever on the carriage projecting above the carriage, a link connecting the control lever with the control, and a pair of spaced stop elements disposed in the path of travel of said operating lever for tripping same upon a predetermined movement of the carriage in either direction.

5. The combination with a lathe having a frame and a carriage reciprocable along the frame, automatic means for driving the carriage, a control for said driving means, a vertically extending operating lever on the carriage and projecting above the carriage, a link connecting the control lever with the control, and a pair of spaced adjustable stop elements disposed in the path of travel of said operating lever for tripping same upon a predetermined movement of the carriage in either direction.

6. The combination with an engine lathe having a clutch, a carriage reciprocable along the bed of the lathe, automatic driving means for the carriage, a control for the carriage drive, and means for simultaneously operating the clutch and the control for the carriage driving means.

7. The combination with an engine lathe having a chuck operating lever thereon and having a carriage reciprocable therealong, and having automatic carriage operating means with a control lever therefor, of an attachment for simultaneously transmitting motion from the chuck operating lever to the said control lever.

8. The combination with an engine lathe having a chuck operating lever thereon and having a carriage reciprocable therealong, and having automatic carriage operating means with a control lever therefor, of an attachment for simultaneously transmitting motion from the chuck operating lever to the said control lever, and a stop mechanism for independently effecting an actuation of the said control lever.

9. The combination with an engine lathe having a chuck operating lever and having a carriage movable along the lathe with automatic means for driving the carriage and means for controlling said driving means, of an attachment comprising a lever pivotally mounted on the carriage, a link connecting the lever with said control means, and a link connecting the lever on the carriage

with the said chuck operating lever, said last mentioned link having a lost motion connection with the chuck operating lever.

10. The combination with an engine lathe having a chuck operating lever and having a carriage movable along the lathe with automatic means for driving the carriage and means for controlling said driving means, of an attachment comprising a lever pivotally mounted on the carriage, a link connecting the lever with said control means, and a link connecting the lever on the carriage with the said chuck operating lever, said last mentioned link having a lost motion connection with the chuck operating lever, and adjustable stops in the path of travel of the lever on the carriage for effecting an operation thereof upon a predetermined movement of the carriage.

11. The combination with an engine lathe having a carriage, carriage driving means, a control for the carriage driving means, a link connected with the control and extending along the carriage, a lever on the other end of the carriage to which the other end of said link is pivotally connected, a second link connected with the opposite end of said lever, a clutch operating lever for the lathe through which the second link is slidably passed, and spaced apart stop elements on the second link for limiting the lost motion between the second link and the said clutch operating lever.

12. The combination with an engine lathe having a carriage, automatic driving means for the carriage, control for said driving means, and having a chuck operating lever, of an attachment therefor comprising a lever pivotally supported on the carriage, a link operatively connecting the said lever on the carriage with the said means for controlling the automatic driving means for the carriage, a link connecting the said lever on the carriage with the said chuck operating lever, said last link having a lost motion connection with the said chuck operating lever, a supporting bar on the lathe, and adjustable stops on the supporting bar in the path of travel of the lever on the carriage for effecting an operation of the lever upon movement of the carriage to a predetermined extent.

13. The combination with a lathe having a head stock, a carriage, means for driving the carriage, a control member for said driving means located at the end of the carriage remote from the head stock, a lever pivotally supported on the carriage at the end nearest the head stock, and a link connecting the lever with said control member.

14. The combination with a lathe having a head stock, a carriage, means for driving the carriage, a control member for said driving means located at the end of the carriage

remote from the head stock, a lever pivotally of said lever, said stops being adapted to supported on the carriage at the end near effect an operation of the lever upon movement of the carriage in either direction to a 10 lever with said control member, and a sup. predetermined extent.

5 porting bar on the lathe, stops on the sup. In testimony whereof I have hereunto set porting bar having cushioned lever engaging my hand. means thereon disposed in the path of travel.

BERNARD J. CALLAN.
